UNITED STATES PATENT OFFICE.

FRANK P. STONE, OF CHICAGO, ILLINOIS.

DESIGN FOR AN AUTOMOBILE-BODY.

41,827.

Specification for Design.

Patented Oct. 3, 1911.

Application filed October 31, 1910. Serial No. 590,091. Term of patent 7 years.

To all whom it may concern:

Be it known that I, FRANK P. STONE, a citizen of the United States, residing at Chicago, in the county of Cook and State of Illinois, have invented a new, original, and ornamental Design for an Automobile-Body, of which the following is a specification, reference being had to the accompanying drawing, forming part thereof.

The figure is a side elevation of an automobile body showing my new design.

I claim:

The ornamental design for an automobile body as shown.

FRANK P. STONE.

Witnesses:

EDNA K. REYNOLDS,
SOPHIE B. WERNER.
